DRUM UPENDER OR SIMILAR ARTICLE

John Oros and Walter H. Moorhead,
Cleveland, OhioSubstituted for abandoned application Serial No.
8,017, February 18, 1950. This application
March 12, 1952, Serial No. 18,856

Term of patent 14 years

(Cl. D54—13)

To all whom it may concern:

Be it known that we, John Oros and Walter H. Moorhead, citizens of the United States, residing at Cleveland, in the county of Cuyahoga and State of Ohio, have invented a new, original, and ornamental Design for a Drum Upender or Similar Article, of which the following is a specification, reference being had to the accompanying drawing, forming part hereof.

This application is a substitute application for design application, Serial No. D. 8,017, filed February 18, 1950, which became abandoned October 6, 1951.

Figure 1 is a view in side elevation of a drum upender or similar article, showing our new design;

Figure 2 is a bottom plan view thereof; and
Figure 3 is a view in front elevation thereof.

We claim:

The ornamental design for a drum upender or similar article, substantially as shown.

JOHN OROS.

WALTER H. MOORHEAD.
